ERNST GEßNER, OF WORCESTER, MASSACHUSETTS

SECTION LINER

Application filed December 31, 1929. Serial No. 417,781.

This invention relates to a device used by mechanical draftsmen in the representation of sectioned surfaces and for other similar purposes.

5 It is the object of my invention to provide a device by which parallel section lines may be quickly and easily drawn at a desired angle and at predetermined distances apart.

10 A further object is to provide a construction by which the angle and the distance between the lines may be readily changed as required for different drafting operations.

15 My invention further relates to arrangements and combinations of parts which will be hereinafter described and more particularly pointed out in the appended claims.

A preferred form of the invention is shown in the drawings, in which

20 Fig. 1 is a plan view of my improved section liner;

Fig. 2 is a side elevation thereof;

Fig. 3 is a sectional end elevation, taken along the line 3—3 in Fig. 1;

25 Fig. 4 is a sectional side elevation, taken along the line 4—4 in Fig. 1;

Fig. 5 is an end elevation of certain modified feeding mechanism;

Fig. 6 is a side elevation thereof;

30 Fig. 7 is a sectional elevation of the feed wheel;

Fig. 8 is a partial side elevation of a modified wheel construction;

Fig. 9 is an end elevation of a further

35 modified feeding mechanism;

Fig. 10 is a sectional side elevation thereof;

Fig. 11 is a sectional elevation of the feed wheel shown in Fig. 10; and

40 Fig. 12 is a partial side elevation of a modified feed wheel.

Referring to the drawings, I have shown a cross bar 20 adapted to extend across a drafting-board and over the drafting paper. Any suitable or customary means may be provided for temporarily holding the bar 20 in a desired convenient position. Parallel guideways 21 are secured to the bar 20 by screws 22 and 23 and extend along the bar 20 for the width of the drafting board.

A carriage 25 is slidably mounted on the guideways 21 and is preferably formed from a single piece of sheet metal bent to a substantially U-shaped section, as indicated in Fig. 3, and having reversely folded flange portions 27 engaging the flanged upper edge portions of the guide members 21. A bracket 30 is welded or otherwise secured to one of the reversely folded flanges 27, as indicated in Fig. 3, and extends downward alongside the adjacent guide member 21.

The lower edge portion of the bracket 30 forms a semi-circular horizontal projection 32 (Fig. 1) provided with a segmental slot 33 and having a ruling arm 34 pivoted at 35 thereon. The edge of the flanged portion 32 is preferably graduated, as indicated at 37, so that the arm 34 may be set at any desired angle. A clamping bolt 38 extends through the arm 34 and slot 33 and is provided with a nut on the under side of the member 32, so that the arm may be firmly secured thereto. The arm 34 must also be graduated on one or both edges in any desired units of length, as indicated at 38^a and 39.

I will now describe the mechanism which I have provided for feeding the carriage 25 longitudinally of the guide members 21. For this purpose a double rack bar 40 (Figs. 1 and 3) is secured to the bar 20 between the guide members 21 by screws 41.

Feed rollers shown as gear wheels 42 are fixed on a sleeve or bushing 43 loosely rotatable on a stud 44 mounted transversely in the carriage 25. The carriage is provided with an opening 46 (Fig. 4) in its lower portion to receive the gear wheels 42.

A feed wheel 50 is fixed on the bushing 43 between the gear wheels 42 and a U-shaped yoke member 52 is loosely pivoted on the bushing 43 at each side of the feed wheel 50. A handle 54 is mounted in the U-shaped member 52 and supports a feed pawl 55 which projects into a groove 56 in the feed wheel 50. The pawl 55 is inclined with respect to a radius of the wheel 50, so that the pawl will frictionally engage the wheel and turn the same when moved to the right in Fig. 4, but will slip idly along the surface thereof when moved in the opposite direction.

Stop bars 60 and 61 are mounted on the carriage 25 and one or both of these stop bars are slideable thereon and may be secured in adjusted position by clamping screws 62. A spring 63 normally pulls the U-shaped member 52 to the left in Fig. 4 until the handle 54 engages the fixed stop 60. When the handle is swung to the right for a feeding movement, the limit of movement is determined by the position of the adjustable stop bar 61. The distance between the lines drawn along the ruling arm 34 is thus determined by the relative position of the stop bars 60 and 61, and by adjusting these bars the lines may be ruled closer or wider apart to suit the conditions of the work to be performed.

If it is desired to use the ruling arm in laying out work and without the feeding mechanism, the pawl 55 may be rendered inoperative by partially unscrewing the handle 54 in the member 52, after which the carriage 50 may be moved freely along its guideways as desired.

In Figs. 5 to 12 I have shown certain modifications of the feeding mechanism. Referring to Figs. 5 to 7, I have shown a construction in which a feed wheel 70 is provided with a face concave in section and provision is made for swinging the feed pawl 71 to one side or the other when it is desired to render the feeding mechanism inoperative.

In Figs. 9 to 11, I have shown a feed wheel 73, preferably having a straight cylindrical outer face as indicated at 74, and engaged by a pawl 75 (Fig. 10) pivoted at 76 to a swinging U-shaped member 77. A handle 78 is secured in the pawl 75, and a spring 79 acts to swing the U-shaped member 77 to the right in Fig. 10 and also to swing the pawl 75 out of engagement with the wheel 73. When pressure is applied to the handle 78 in the direction of the arrow *a* in Fig. 10, the pawl is forced against the periphery of the wheel 74 and the wheel is turned in the direction of the arrow *b* in Fig. 10.

As soon as the handle is released, the spring 79 disengages the pawl 75 and also swings the U-shaped member 77 to the right. With this construction, the pawl 75 is entirely free from the wheel 73 on and after its idle return movement but instantly engages the feed wheel 73 when swung to the left. The carriage may be moved freely when the feed pawl is in its return position.

In Figs. 8 and 12, I have indicated that the feed wheels shown in Figs. 6 and 10 may be provided with ratchet teeth 80 if it is desired to have a more positive engagement between the pawl 71 or 75 and the feed wheel 70 or 73. Scales 85 and 86 (Figs. 1 and 2) may be provided for determining the exact amount of feed of the carriage 25.

Additional scales 87 and 88 may be provided on the upper surface of the carriage 25 to be used in the setting of the stop bars 60

or 61. These scales 87 and 88 are graduated so that a movement of the stop one graduation of the scale 87 or 88 will cause a change in feed of the carriage equal to one graduation of the corresponding direct-reading scale 85 or 86.

It will be seen that I have provided a section liner construction in which the arm 34 may be set at any desired angle and in which the carriage 25 may be fed step by step, advancing the arm 34 a predetermined distance for each feeding operation.

It will be further evident that the feeding mechanism may be readily thrown out of operation if desired, so that the carriage 25 and arm 34 may be moved freely back and forth across the drafting-board for any desired purposes.

Having thus described my invention and the advantages thereof, I do not wish to be limited to the details herein disclosed, otherwise than as set forth in the claims, but what I claim is:—

1. A section liner comprising guide members, a carriage slideable on said guide members, a ruling arm mounted on said carriage, and means to propel said carriage a predetermined distance along said guideway at each actuation of the propelling means, said means comprising a feed roller mounted in the carriage, a U-shaped support mounted to swing upon the axis of said roller, a feed wheel mounted between the spaced parts of said support and rotatable with said roller, a pawl mounted on said support and engageable with said wheel and a handle by which said pawl may be engaged with said wheel to give a feeding movement thereto, and adjustable means to limit the movement of said handle.

2. A section liner comprising guide members, a carriage slideable on said guide members, a ruling arm mounted on said carriage, a feeding roller mounted in said carriage, and means to turn said roller to advance said carriage and ruling arm, said turning means having threaded adjustment effective to release said roller from said turning means for free rotation in either direction.

3. A section liner comprising guide members, a carriage slideable on said guide members, a ruling arm mounted on said carriage, a feeding roller mounted in said carriage, means to turn said roller to advance said carriage and ruling arm a predetermined distance, a stop limiting movement of said turning means in one direction, and an adjustable stop by which the amount of turning movement may be varied and determined, said turning means having a threaded adjustment effective to release said roller from said turning means for free rotation in either direction.

4. A section liner comprising guide members, a carriage slideable on said guide mem-

bers, a ruling arm mounted on said carriage, a feeding roller mounted in said carriage, and interengaging means between said members and said roller, and means to turn said roller to advance said carriage and ruling arm, said turning means comprising a U-shaped support mounted to swing upon the axis of said roller, a feed wheel mounted between the spaced parts of said swinging support and rotatable with said roller, a pawl pivoted on said support, a spring effective to return said support to initial position and to move said pawl free from said roller, and a handle by which said pawl may be engaged with said roller and said support and pawl may be given a feeding movement against the tension of said spring.

5. A section liner comprising guide members, a carriage slideable on said guide members, a ruling arm mounted on said carriage, a feeding roller mounted in said carriage, and means to turn said roller to advance said carriage and ruling arm comprising an actuating pawl, and a handle attached thereto, 20 and a threaded support for said handle whereby the handle may be adjusted to retract the pawl and leave the roller free to rotate in either direction.

6. A section liner comprising guide members, a carriage slideable on said guide members, a ruling arm mounted on said carriage, a feeding roller mounted in said carriage, and means to turn said roller to advance said carriage and ruling arm comprising an actuating pawl mounted to swing transversely of the roller, whereby the roller may be left free to rotate in either direction.

In testimony whereof I have hereunto affixed my signature.

40 ERNST GEßNER.
